UNITED STATES PATENT OFFICE.

JAMES CARNEGIE, OF PASSAIC, WILLIAM J. KENNEDY, OF JERSEY CITY,
AND HENRY L. EBSEN, OF HOBOKEN, NEW JERSEY.

BOILER.

SPECIFICATION forming part of Letters Patent No. 650,966, dated June 5, 1900.

Application filed December 8, 1898. Serial No. 698,658. (No model.)

To all whom it may concern:

Be it known that we, JAMES CARNEGIE, residing at Passaic, in the county of Passaic, WILLIAM J. KENNEDY, residing at Jersey City, in the county of Hudson, and HENRY L. EBSEN, residing at Hoboken, in the county of Hudson, State of New Jersey, citizens of the United States, have invented a new and useful Boiler, of which the following is a specification.

Our invention relates to boilers; and the object thereof is to provide a boiler especially adapted for marine purposes in which the steam-generating capacity shall not be diminished, and is even increased, while the liability to collapse by the destruction of the stays supporting the walls of the combustion-chamber is obviated, the weight of the boiler is decreased, and a more rapid circulation is effected, the water being drawn from the parts of the boiler where there is a less degree of heat and discharged into the boiler highly heated. We attain these objects by the mechanism illustrated in the accompanying drawings, in which—

Figure 1 is a longitudinal sectional view in elevation of a boiler constructed according to our invention. Fig. 2 is a rear end view of the same, the combustion-chamber and part of the tubes being in section; and Fig. 3 is a plan view of the tubes in the combustion-chamber at the rear end of the boiler.

In the drawings similar numerals of reference refer to the same parts in each of the views, and in the practice of our invention we provide a boiler which consists of a cylindrical shell 5, inclosed at each end 6 and 7 and provided with tubular fire-chambers 8, 9, and 10, each of which is provided with fire-grates. (Not shown, as this part of the construction is well known.) The boiler is also preferably provided with a plurality of tubes 11, through which the heated gases of combustion pass, as indicated by the arrows.

In the rear of the cylindrical shell 5 we construct a chamber 12, the walls of which consist of fireproof non-conducting material 13, and is preferably inclosed by a steel casing 14. In the bottom of the chamber 12 we mount a large tube 15, which is connected with the sides of the cylindrical part of the

boiler by tubes 16, which are prolonged inside the said cylindrical part, as shown at 17, and take in water from any desired point, as shown at 18; and the tube 15 is connected with the said cylindrical part by other tubes 19, which are prolonged inside the said cylindrical part, as shown at 20, and take in water from the bottom of the cylindrical part, preferably near the front end thereof, as shown at 21.

Connected with the tubes 19 are a plurality of small tubes 22, which are connected with drums or headers 23 at the top of the chamber 12 and which are connected with the cylindrical part of the boiler, as clearly shown. We also connect with the tube 15 a plurality of tubes 24, which are bent or curved at the upper end thereof, as shown at 25, and are connected with and discharge into the cylindrical part of the boiler, as shown at 26, or the tubes 24 may be connected with tubular stays 27, which may be provided with ports or openings 28 at any desired point, so that the water and steam may be discharged near the front end of the cylindrical part, if desired.

The operation is as follows: The combustion of the fuel takes place in the tubular fire-chambers 8, 9, and 10, and the combustion of the gases is continued in the chamber 12, from whence the heated gases pass through the tubes 11 into the smoke-stack 29. As shown in the drawings, all the heated gases pass through the tubes 11; but it is not essential that there should be any tubes 11.

By this construction the water will be heated to a greater degree at the top of the boiler than at the bottom and at the rear end than at the front and at the center than at the sides. For this reason the prolongations 17 and 20 of the tubes 16 and 19 are provided, so that the water is taken into the said tubes from the coldest part of the boiler, and as it passes through the tube 15 and tubes 22 and 24 it is heated to a much higher degree than the water in the cylindrical part, and consequently is carried upward and discharged into the boiler or cylindrical part thereof with great rapidity and thorough circulation is guaranteed. In the drawings all the tubes 22 and 24 and drums 23 are shown as being discharged

into the cylindrical part of the boiler below the water-level; but this is not absolutely essential. Where the tubes 24 are connected with the tubular stays 27, the heated water from 5 the said tubes can be delivered at or near the front of the cylindrical part, as will be plainly seen.

By this construction we avoid the inclosing of the combustion-chamber connecting the 10 fire-chambers with the flues within the boilers—a great weakness in marine boilers now in use—and at the same time the heating-surface is greatly increased while the weight of the boiler is diminished.

15 As it is evident that many changes may be made in the construction and arrangement of tubes in the chamber 12 and in the disposition of said chamber without departing from the spirit of our invention, we reserve the 20 right to make all changes which fairly come within the scope of the said invention.

Having fully described our invention, what we claim, and desire to secure by Letters Patent, is—

25 1. A boiler comprising a cylindrical part having inclosed fire-chambers, a combustion-chamber mounted at the rear end of said cylindrical part, tubes mounted in said combustion-chamber, said tubes being in communication with said cylindrical part at or near the bottom of said chamber, and also being connected with said cylindrical part at or near the top of said chamber, and tubular stays in said cylindrical part with which part 30 of said tubes in said combustion-chamber are connected, said tubular stays being provided with ports or openings, substantially as and for the purpose described.

2. A boiler comprising a cylindrical part 40 having inclosed fire-chambers, a combustion-chamber mounted at the rear end of said cylindrical part, a large tube mounted in the bottom of said combustion-chamber, short tubes connecting said large tube with the said cylindrical part, and provided with extensions inside of said cylindrical part, said extensions being in communication with the interior of said boiler at predetermined points, a plurality of tubes connected with the large 45 pipes at the bottom of said combustion-chamber, said tubes being also connected with the said cylindrical part at or near the upper end of said chamber, substantially as and for the purpose set forth.

50 3. A boiler comprising a cylindrical part

having inclosed fire-chambers, a combustion-chamber mounted at the rear end of said cylindrical part, a large tube mounted in the bottom, and at the rear side of said combustion-chamber, short tubes connecting said 60 large tube with the said cylindrical part, said short tubes being provided within said cylindrical part with extensions which communicate with the interior of the boiler at predetermined points, a plurality of tubes connected with said large tube and provided at the upper end thereof with curved portions, the ends of which are connected with said cylindrical part, drums mounted at the top of said combustion-chamber and in communication with the interior of said cylindrical part, and a plurality of tubes connecting said drums with the short tubes at the bottom of said chamber, substantially as and for the 70 purpose described.

4. A boiler comprising a cylindrical part having inclosed fire-chambers, a combustion-chamber mounted at the rear end of said cylindrical part, a large tube mounted in the bottom and at the rear side of said combustion-chamber, short tubes connecting said large tube with the said cylindrical part, said short tubes being provided within said cylindrical part with extensions which communicate with the interior of the boiler at predetermined points, a plurality of tubes connected with said large tube and provided at the upper end thereof with curved portions, the ends of which are connected with the said cylindrical part, tubular stays in said cylindrical part, and part of said last-named tubes being connected with said stays which are provided with ports or openings at predetermined points, drums mounted at the top of said combustion-chamber and in communication with said cylindrical part, and a plurality of tubes connecting said short tubes at the bottom of the chamber with said drums, substantially as and for the purpose described.

In testimony that we claim the above we have hereto affixed our signatures in the presence of two witnesses.

JAMES CARNEGIE.
WILLIAM J. KENNEDY.
HENRY L. EBSEN.
